UNITED STATES PATENT OFFICE.

GEORGE E. THACKRAY, OF WESTMONT, PENNSYLVANIA.

DIE FOR DRAWING METAL RODS.

SPECIFICATION forming part of Letters Patent No. 686,365, dated November 12, 1901.

Application filed December 6, 1899. Serial No. 739,398. (No model.)

To all whom it may concern:

Be it known that I, GEORGE E. THACKRAY, a citizen of the United States, residing at Westmont, in the county of Cambria and State of Pennsylvania, have invented certain new and useful Improvements in Dies for Drawing Metal Rods and Bars; and I do hereby declare the following to be a full, clear, and exact description of the invention, such as will enable others skilled in the art to which it appertains to make and use the same.

The object of my invention is to provide new and improved forms of sectional or adjustable drawing-dies for use in drawing metal rods or bars for the purpose of giving their surfaces an accurate form and finish or for increasing their strength and elastic limit or for successively reducing the section, as in wire-drawing.

20 My invention has special reference to dies for drawing rectangular or square bars, rods, or wire, although it may also be adapted and applied for use in drawing other bars of regular or irregular polygonal or other section, as may be readily understood.

Although my invention may be adapted for use in drawing rods or bars of various cross-sections, as above described, in order to simplify my description I will refer herein only to that form which is adapted for use in drawing square or rectangular bars, the adaptation and arrangement for other sections than these being obvious.

My improved die consists of four die-blocks, 35 preferably of pentagonal form, each block being formed with one of its edges convex or rounded to serve as a working face, while one of the edges adjoining said convex face is concaved in such a way as to fit the convex surface of the adjoining die-block.

The principal flat surface of the die-block which I prefer to use has the general appearance of a rectangle with two of its adjoining corners cut off in such a way as to form a surface ending in a right angle, and although not strictly essential I prefer the form in which one corner is cut off more than the other. The longer of the two angular edges of each die-block formed as above described is preferably made convex to serve as a working face;

while the other and adjoining angular edge is concave to fit the adjoining die-block, as hereinbefore referred to.

I prefer to make the die-blocks of such shape that the angular edges are inclined forty-five degrees to the sides of the original rectangle above referred to, although I do not limit myself to this angle.

To form a square or rectangular die, I use four of the above-described angular die-blocks which are contained within a die-plate provided with a recess therefor of substantially square outline, but provided with inclined faces at or near the corners to serve as bearings for the adjusting-wedges, one wedge being provided to bear against each die-block and the adjoining surface of the die-plate for the purpose of adjusting the former within the latter.

If the surfaces of the die-blocks where they bear against the surfaces of the recess in the die-plate are accurately fitted, only one wedge is necessary to complete the adjustment, as by means of this the movement of one block would determine the motion of all, as may be readily understood by inspection of the drawings. In order, however, to avoid the necessity for the most accurate fitting, I prefer to provide, as above mentioned, one adjusting-wedge for each of the die-blocks, and in addition I also preferably provide other wedges which bear against the ends of two or more adjoining die-blocks in order to take up any lost motion caused by the loose fitting of the die-blocks within the recess formed in the die-plate.

The old and present form of die-block for use in drawing square bars is made from a solid plate which is difficult to manufacture, as the work on the interior surface of the working face has to be done by hand, owing to the smallness and shape of the aperture, which does not permit of machine-work. In addition to this said solid dies are difficult to repair or renew when they become worn, as any slight imperfection in their working surfaces is sufficient to destroy their usefulness. On the other hand, the working and other surfaces of my improved form of sectional die-blocks are straight and accessible

in such a way that they can readily be trued up on a grinding-machine or other suitable tool when worn by use.

After my dies have been so worn as to be temporarily useless I can grind their surfaces easily, as above described. This grinding somewhat reduces the size of each block, which reduction, however, is provided for by the use of the adjusting-wedges aforesaid, which compensate for this change of size within reasonable limits, as may be readily understood.

The wedges which I prefer to use may either be formed with single or double taper and provided with threaded bolt ends the nuts of which bear either directly or indirectly against the rear faces of the die-plate before mentioned.

In order to provide ready means of alining the center of my dies, I prefer to make the die-plate and its holder in the form of a segmental ball and socket adjustable by means of set-screws in a hinged gate forming part of the head-block of a drawing-machine. Although I prefer to use a die-plate so formed as to be adjusted in the manner above described, I do not consider this part of my invention and do not claim it herein.

Although in certain cases the wedges may be formed with bolts and nuts for adjusting and taking up the lost motion in my die-blocks, I do not limit myself to this exact construction, as I may use wedges without the bolts or set-screws working in threaded holes formed in the die-plate and bearing against the edges of my adjustable die-blocks, or, in fact, any suitable means for adjusting and holding the die-blocks in a suitable position with relation to one another, as may be readily understood.

Having given this general description of my invention, I will now refer to the annexed three sheets of drawings, which form part of this specification, and in which like letters refer to like parts.

Figure 1 is a general front elevation showing my die-blocks in position within the die-plate, all being contained in the head-block of a drawing-machine preferably provided with a hinged gate and means for adjusting the alinement of the dies. Fig. 2 is a central cross-section through the die-plates, blocks, and head on line 2 2 of Fig. 1. Fig. 3 is a front elevation of my die-blocks contained within a die-plate similar to the view of these parts shown in Fig. 1, with head-block removed, but showing the same dies adjusted to produce a bar of smaller section. Fig. 4 is a front elevation showing an arrangement of dies to produce a rectangular section. Fig. 5 is a front elevation of a modified arrangement of my die-blocks and die-plate, each die-block in this case being provided with an adjustable wedge at one side and another wedge at the end, the latter serving to take up the lost motion and preserve the central

position of the draw-hole. Fig. 6 is a cross-section taken on the line 6 6 of Fig. 5. Fig. 7 is an arrangement of my die-block in which but one side wedge and four end wedges are used. Fig. 8 is an arrangement of my die-block in which plain side wedges are used for adjustment of the blocks, together with a stop-block or wedge. Fig. 9 is a cross-section taken on line 9 9 of Fig. 8. Fig. 10 is an arrangement of my die-block in which set-screws are used for the adjustment of the blocks. Fig. 11 is a cross-section taken on line 11 11 of Fig. 10.

In the different figures A A A A are my die-blocks provided with the convex working surfaces B.

C is the die-plate.

D D D D are adjusting-wedges bearing against the sides of the blocks A and the inner surface of the recess formed in the die-plate C, each of said die-blocks being provided with a concave edge, as shown, closely fitting against the convexity of the adjoining die-block.

D' is a wedge or stop fitting between one of the wedges D and one of the die-blocks A. Said stop D', acting in conjunction with the wedges D, serves to secure the die-blocks in position, the wedges D holding the die-blocks from moving in one direction, while the stop D' prevents their motion in the opposite direction, as may be readily understood.

In Fig. 3, E E are wedges bearing against the ends of two of the die-blocks A, which wedges are used in adjusting and taking up the lost motion of the die-blocks within the recess formed in the die-plate C.

In Fig. 5 four wedges E are shown, corresponding to those similarly lettered in the other figures, and in Fig. 7 are four similar wedges marked E'.

In adjusting my die, as shown in Figs. 1, 2, 3, 5, and 6, for a given size I prefer to make the first adjustment by means of one or more of the wedges D in connection with the stop D', after which the wedges E E are tightened up, thereby completing the adjustment. The adjustment of my die (shown in Fig. 4) is made by means of the wedges D and the stop-wedge D'. The die shown in Fig. 7 is adjusted by means of the wedge D and the end wedges E'. The die shown in Figs. 8 and 9 is adjusted by means of the plain wedges D² and the stop D³, and that shown in Figs. 10 and 11 is adjusted by means of the set-screws P and Q.

Fig. 7 shows an alternative arrangement of my die-blocks, in which three of the wedges D are dispensed with, the wedges E' E' E' E' in this case serving a similar purpose, said wedges E' being contained within an offset formed in the die-plate, as shown, in order to properly preserve the position of each with relation to the other parts. In this case I prefer to use one wedge similar to that hereinbefore described and which is lettered D in Fig. 7, above referred to, and another similar one

may be used to act in a contrary direction, as may be readily understood.

In the case shown in Fig. 7 the wedges E' serve for the adjustment of the die-blocks 5 and also for keeping them in close contact with each other after the manner hereinbefore described. This arrangement of four wedges E' may, however, be modified by omitting two of said wedges, the only difference in this 10 case being that the draw-hole will not remain central with respect to the die-plate; but where this is immaterial the latter arrangement is to be preferred, as it is in the direction of simplicity.

15 F F are threaded bolt ends forming part of the various wedges. G G are the nuts of the same, while J J are washers interposed between said nuts and the rear surface of the die-plate C, said bolts passing through the 20 slotted holes I I, formed in the die-plate.

Referring now to Figs. 8 and 9, D² D² D² D² are plain wedges for adjusting and securing the die-blocks A, and D³ is a stop for adjusting and holding said die-blocks in the oppo- 25 site direction.

As shown in Figs. 10 and 11, P P P P are set-screws for adjusting and securing the die-blocks A, and Q Q are other set-screws for securing and adjusting the same endwise, 30 and in this construction the die-plate C is made thicker to accommodate the set-screws without interfering with the support of said plate within the head-block K. (Shown in Figs. 1 and 2.)

35 K is a head-block of a drawing-machine provided with a segmental spherical socket K', into which the die-plate C is fitted, as shown in Fig. 2.

L is a hinged gate attached to the head- 40 block K by means of the bolt M; said bolt being provided with a key N for retaining it in place.

O is a locking-bolt which by means of the nut P secures the hinged gate L to the head- 45 block K, said hinged gate being provided with set-screws H H H H, working in threaded holes therein, their ends bearing against the die-plate C for the purpose of adjusting the same in proper position within the head- 50 block.

In order to provide a ready means for setting my die-blocks to the size required, I may use a male templet or block of the same size as that which is proposed to be drawn, said 55 templet being inserted within the draw-hole and the die-blocks brought into firm contact therewith by means of the wedges or set-screws, as above described, after which the templet may be withdrawn and the die is 60 ready for operation.

Having thus described my invention, what I claim, and desire to secure by Letters Patent, is—

1. In a die-block, the combination with a 65 plate, of a series of polygonal blocks, adjustably mounted therein, each of said blocks being provided with contiguous convex die and

concave contact surfaces, clamping-surfaces on said blocks, one of said clamping-surfaces being arranged at an angle with both said die 70 and contact surfaces, and adjusting means for a plurality of said blocks.

2. In a die-block, the combination with a plate, having a square recess therein, of a series of polygonal blocks, adjustably mounted 75 within said recess, each of said blocks being provided with contiguous convex die and concave contact surfaces, clamping-surfaces on said blocks, one of said clamping-surfaces being arranged at an angle with both said die 80 and contact surfaces, and adjusting means for a plurality of said blocks.

3. An adjustable die-block comprising a die-plate, a series of blocks adjustably mounted therein, each of said blocks being provided 85 with contiguous convex die and concave contact surfaces, clamping-surfaces on said blocks, one of said clamping-surfaces being arranged at an angle with both said die and contact surfaces, and adjusting means for a 90 plurality of said blocks.

4. An adjustable die-block comprising a die-plate, a series of blocks adjustably mounted therein, each of said blocks being provided with a convex die-surface and a concave contact-surface contiguous thereto, a clamping-surface on two or more of said blocks, arranged 95 at an angle to both said die and contact surfaces; and adjusting means for a plurality of said blocks. 100

5. An adjustable die-block, comprising a die-plate, a series of blocks mounted therein, each of said blocks being provided with a convex die-surface, a concave contact-surface contiguous thereto and a clamping-surface ar- 105 ranged at an angle to both said die and contact surfaces; a plurality of wedges bearing against said die-plate and the clamping-surfaces of said die-blocks.

6. An adjustable die of the class described, 110 comprising a die-plate, a series of blocks adjustably mounted therein, each of said blocks being provided with a convex die-surface, a concave contact-surface contiguous thereto, clamping-surfaces on said blocks, one of said 115 clamping-surfaces being arranged at an angle to both said die and contact surfaces; and a plurality of wedges for clamping and adjusting said die-blocks within said die-plate.

7. In an adjustable die, the combination 120 with a die-plate, of a series of blocks, each provided with a convex die-surface, a concave contact-surface contiguous thereto, and clamping-surfaces, one of said clamping-surfaces being arranged at an angle to both said 125 die and contact surfaces; and means acting on said clamping-surfaces for clamping and adjusting a plurality of said die-blocks.

8. A die composed of a number of blocks, each having a convex die-surface, a concave 130 contact-surface adjoining the same and made to fit the convexity of the adjoining block, a plurality of said blocks being each provided with a clamping-surface arranged at an angle

with both said die and contact surfaces, and adjusting means for a plurality of said blocks.

9. A die composed of a number of blocks, 5 each having a convex die-surface, a concave contact-surface adjoining the same and made to fit the convexity of the adjoining block, a plurality of said blocks being each provided with a clamping-surface arranged at an angle 10 with both said die and contact surfaces, in combination with a die-plate and adjusting means for a plurality of said die-blocks.

10. A die composed of a number of blocks, each having a convex die-surface, a concave 15 contact-surface adjoining the same and made to fit the convexity of the adjoining block, clamping-surfaces, one of which is arranged at an angle with both said die and contact surfaces, in combination with a die-plate and 20 wedges bearing against the clamping-surfaces of a plurality of said die-blocks.

11. In an adjustable die, the combination with a die-plate, of a number of blocks, each having a convex die-surface, a concave contact-surface adjoining the same and made to fit the convexity of the adjoining block, clamping-surfaces one of which is arranged at an angle with both said die and contact surfaces, wedges bearing against the clamping-surfaces 25 of two or more of said die-blocks and threaded bolts and nuts on said wedges for adjusting the same.

12. In an adjustable die the combination with a die-plate, of a number of blocks adjustably mounted therein, each block having 30 a convex die-surface, a concave contact-surface

adjoining the same and made to fit the convexity of the adjoining die-block, each block being further provided with two clamping-surfaces angularly arranged with respect 40 to said die and contact surfaces, and adjusting devices bearing against said die-plate and the two clamping-surfaces of said die-blocks.

13. In an adjustable die the combination with a die-plate, of a number of blocks adjustably mounted therein, each of said blocks being provided with a die-surface, a contact-surface contiguous thereto, clamping-surfaces, one of which is arranged at an angle to both said die and contact surfaces, a plurality 45 of adjusting means arranged in said die-plate and adapted to adjust said blocks by means of their surfaces aforesaid.

14. In an adjustable die, the combination with a die-plate, of a number of blocks mounted therein, each block having a convex die-surface, a concave contact-surface adjoining the same and made to fit the convexity of the adjoining block, side and end clamping surfaces on said blocks angularly arranged with 50 respect to both said die and contact surfaces, a plurality of wedges adapted to bear against said die-plate and the clamping-surfaces of said die-blocks for the purpose of adjusting and securing the same. 55

In testimony whereof I affix my signature in the presence of two witnesses.

GEORGE E. THACKRAY.
